(57) **CLAIM**

The ornamental design for a golf club head, as shown and described.

DESCRIPTION

FIG. 1 is a rear bottom perspective view of the golf club head;

FIG. 2 is a rear elevational view thereof;

FIG. 3 is a heel-side elevational view thereof;

FIG. 4 is a toe-side elevational view thereof; and,

FIG. 5 is a bottom plan view thereof.

The broken lines depict parts of the golf club head that form no part of the claimed design. The dot-dash chain lines depict boundaries of the claimed subject matter, and thus form no part of the claimed design.
